UNITED STATES PATENT OFFICE.

ELIAS ISRAEL, OF NEW YORK, N. Y.

DESIGN FOR BRAID.

47,396.

Specification for Design.

Patented June 1, 1915.

Application filed March 20, 1915. Serial No. 15,961. Term of patent 3½ years.

To all whom it may concern:

Be it known that I, ELIAS ISRAEL, a subject of the Czar of Russia, residing at New York city, county of New York, and State of New York, have invented a new, original, and ornamental Design for Braid, of which the following is a specification, reference being had to the accompanying drawing, forming part thereof.

The drawing is a front or face view of a piece of braid embodying my invention enlarged beyond the size of the braid as usually made.

I claim:

The ornamental design for braid, as shown.

In witness whereof, I have hereunto set my hand in the presence of two witnesses.

ELIAS ISRAEL.

Witnesses:

E. H. JACOBSON,
PETER C. MANY.
